WHISTLE

John F. Chmela, 7256 W. Davis St., Morton Grove, Ill. 60053, and Joseph E. Schiltz, 42 S. Cypress Drive, Bristol, Ill. 60512

Filed Aug. 13, 1968, Ser. No. 13,128

Term of patent 14 years

Int. Cl. D21—02

U.S. Cl. D34—15

FIG. 1

FIG. 2

FIG. 3

FIG. 4

FIG. 5

FIG. 7

FIG. 6

FIGURE 1 is a top perspective view of a whistle showing our new design;

FIGURE 2 is a top plan view thereof;

FIGURE 3 is a bottom plan view thereof;

FIGURE 4 is a sectional view taken along lines 4—4 of FIGURE 2;

FIGURE 5 is a sectional view taken along lines 5—5 of FIGURE 2;

FIGURE 6 is a sectional view taken along lines 6—6 of FIGURE 2; and

FIGURE 7 is a partial perspective view, illustrating the whistle chamber integrally formed with the whistle of FIGURE 1.

The broken lines in FIGS. 4, 5 and 6 indicate the level plane.

We claim:

The ornamental design for a whistle, as shown and described.
